(57) **CLAIM**

The ornamental design for a ceiling fan blade iron, as shown and described.

DESCRIPTION

FIG. 1 is a perspective view from below of the ceiling fan blade iron in accordance with my design, illustrating the environment of the invention;

FIG. 2 is an enlarged bottom plan view of the ceiling fan blade iron illustrating the environment of the blade iron in accordance with my design.

FIG. 3 is an enlarged bottom plan view of the ceiling fan blade iron in accordance with my design, illustrating the environment of the invention;

FIG. 4 is a greatly enlarged left side elevation view of the ceiling fan blade iron in accordance with my design, illustrating the environment of the invention;

FIG. 5 is a greatly enlarged right side elevation view of the ceiling fan blade iron in accordance with my design;

FIG. 6 is a greatly enlarged perspective view from above of the ceiling fan blade iron, in accordance with my design; and,

FIG. 7 is an greatly enlarged end view of the ceiling fan blade iron in accordance with my design.

The surfaces of the ceiling fan blade iron that attach to the ceiling fan blade are flat and unadorned and no claim thereto is made.

The broken line showing of environmental structure in FIGS. 1–6 is for illustrative purposes only and forms no part of the claimed design.
